UNITED STATES PATENT OFFICE.

CHARLES T. WESTLAKE, OF ST. LOUIS, MISSOURI, ASSIGNOR TO LOCOMOTIVE TENDER FRAME COMPANY, OF ST. LOUIS, MISSOURI, A CORPORATION OF DELAWARE.

TENDER END SILL.

1,027,784.

Specification of Letters Patent. Patented May 28, 1912.

Application filed December 16, 1911. Serial No. 666,154.

To all whom it may concern:

Be it known that I, CHARLES T. WESTLAKE, a citizen of the United States, residing at St. Louis, Missouri, have invented a certain new and useful Improvement in Tender End Sills, of which the following is a full, clear, and exact description, such as will enable others skilled in the art to which it appertains to make and use the same, reference being had to the accompanying drawings, forming part of this specification, in which—

Figure 1 is a top plan view of my improved tender end sill. Fig. 2 is a front elevational view, partly in section, of my improved tender end sill. Fig. 3 is an end elevational view of the same.

This invention relates to a new and useful improvement in end sills designed particularly for tender underframes, and while shown as a separate casting in the drawings, it could be an integral part of the underframe.

The particular feature of my present invention is the provision of step extensions at each end of the end sill, said extensions being preferably integral with the end sill, provided with means for retaining wooden treads, which latter are bolted or otherwise secured in position. These wooden treads, of course, could be replaced by integral metal treads, if desired.

In the drawings, 1 indicates the end sill which may be of any approved construction with respect to its interior bracing members, but preferably this end sill has front and rear vertical walls 2 and 3, which at the end sills are extended downward as at 4 to form supports for the stops.

The end wall of the end sill is cut away 40 as at 5 to provide a flat opening, and on the bottom wall 6 are preferably arranged flanges 6^a constituting retaining walls for the tread portion 7. Other flanges 6^b are arranged at different points to support similar treads 7.

I claim:

1. An end sill, having its end wall removed so that the bottom wall thereof will constitute a tread, said end sill having integral 50 downward extensions at each end, said extensions being also provided with treads.

2. The combination with an end sill having open ends so that the end portions of its bottom wall constitute treads and removable tread plates positioned on the end portions of said bottom wall.

3. An end sill having its end wall removed so that the bottom wall thereof constitutes a step, tread plates applied to the 60 end portions of the bottom wall, depending walls at the ends of said end sill, transversely disposed plates between said depending walls, and removable tread plates positioned on said transversely disposed 65 plates.

4. A cast metal end sill having its ends open so that the end portions of the bottom wall of said sill form steps, and tread plates applied to the end portions of said bottom 70 wall.

In testimony whereof I hereunto affix my signature in the presence of two witnesses, this 13th day of November, 1911.

CHARLES T. WESTLAKE.
